US00D882523S

(12) **United States Design Patent** (10) **Patent No.:** **US D882,523 S**
Li (45) **Date of Patent:** **** Apr. 28, 2020**

(54) **CONNECTOR**

(71) Applicant: **Getac Technology Corporation**,
 Hsinchu County (TW)
 (72) Inventor: **Chun-Hsing Li**, Taipei (TW)
 (73) Assignee: **GETAC TECHNOLOGY
 CORPORATION**, Hsinchu County
 (TW)

(**) Term: **15 Years**

(21) Appl. No.: **29/655,582**

(22) Filed: **Jul. 5, 2018**

(30) **Foreign Application Priority Data**

Jan. 5, 2018 (CN) 2018 3 0004578

(51) **LOC (12) Cl.** **13-03**

(52) **U.S. Cl.**

USPC **D13/147**

(58) **Field of Classification Search**

 Tingkang Xia, Esq.

(57) **CLAIM**

The ornamental design for a connector, as shown and
 described.

DESCRIPTION

FIG. 1 is a perspective view of a connector showing the
 claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

In the drawings, the broken lines show portions of a
 connector that form no part of the claim.

1 Claim, 7 Drawing Sheets
